UNITED STATES PATENT OFFICE.

PAUL SCHERTL, OF HOBOKEN, NEW JERSEY.

SAFETY POCKET.

Application filed February 25, 1925. Serial No. 11,399.

The main object of this invention is to provide a secret pocket in trousers which is calculated to be deceptive to holdup men and pickpockets.

5 Another object is to provide an additional pocket to the pockets now in use with trousers which is so concealed that it is not ordinarily apparent it exists.

Still another object is to provide a pair 10 of pockets which bind at their mouths, one of which is provided with a lapping piece of material forming part of the trousers which cooperates with the portion of this pocket and is adapted to lock the same so 15 that said pocket remains invisible.

The above and other objects will become apparent in the description below, in which characters of reference refer to like-named parts in the drawing.

20 Referring briefly to the drawing, Figure 1 is a front elevational view of the trousers, showing the position of the secret pocket therein.

Figure 2 is an enlarged perspective view 25 of the trousers, parts being broken away showing the construction of the secret pocket and the usual pocket.

Figure 3 is a sectional top plan view of the trousers as equipped with the secret 30 pocket.

Referring in detail to the drawing, the numerals 10 and 11 indicate the legs of a pair of trousers which are joined at their upper ends by an integral portion of the 35 trousers material which is adapted to fit and cover the waist. This portion of material which covers the waist is usually provided with side pockets 12 at both sides of the trousers above each leg. These side pockets 40 are entered thru a slit 13 which is usually of a size large enough to permit the ready insertion of the fist thru the slit. The pocket 12 is usually comprised of a double piece of lining which presents a pair of ad- 45 jacently formed walls 14 and 15 which encloses a chamber 16 in which miscellaneous articles may be stored on the person. In wearing a pair of trousers, the slit 13 of the pockets is usually spread apart slightly, and 50 if a strip of material 17 were not provided, the lining material forming the pocket walls 14 and 15 could be seen and would be considered as unsightly. This strip of material 17 is of the same material as the body 55 of the trousers and is stitched to said body at 18 on one longitudinal edge and is usually

free at its opposite longitudinal edge. The secret pocket is of the same dimensions as the pocket 12 and lies directly behind the latter so as to be at all times concealed by the 60 usual type of pocket. This secret pocket is comprised of the same material as the pocket 12 and is formed on a doubled length of the material which provides parallel adjacent walls 19 and 20 between which the 65 chamber 21 of the secret pocket is formed. The longitudinal edge of the wall 19 of the secret pocket is stitched to the inside surface of the strip 17 at 22, the stitch running downwardly thruout the entire length of 70 the pocket. The opposite wall 20 of the secret pocket and the wall 15 of the ordinary pocket are stitched together at 23, and the surface of the wall 15 of the usual pocket which may be seen by looking into the slit 75 13 is provided with resilient button members 24 which cooperate with complementary button members 25 which are sewed to a strip 17, the buttons 24 when interlocked with the members 25 being adapted to close 80 and lock the secret pocket 21. Within the secret pocket between the strip 17 and the wall 19, resilient doubled metallic fingers 26 have their ends secured or sewn respectively to the wall 19 of the secret pocket and the 85 finishing strip 17 and is adapted to spread the wall and strip apart and away from each other when the locking members 24 and 25 are released.

The pocket is used in the following manner. When desiring to open the pocket, the hand is inserted thru the slit 13 of the usual pocket with the fingers in clenched position. As the finger nails pass the free edge 90 of the longitudinal strip 17, and slide down 95 upon the surface of the wall 15 of the usual pocket the fingers are then in position to grasp the edge of the pocket. By reversing the movement of the hand, that is, by pulling the hand out again with the fingers in 100 clenched position, the clenched fingers engage the edge of the strip 17 and lift said strip so that the locking members 24 are disengaged from the locking members 25 of the strip 17 and the pocket is spread open 105 by the resilient fingers 26 so that ready access may be had to the chamber 21 of the secret pocket thru the usual pocket 12.

I claim:—

In trousers, the usual side pockets and 110 entering slits for said side pockets, a secret pocket concealed in the side pocket com-

prising a doubled length of material forming a pocket directly behind and concealed beneath the usual side pocket, one side of the usual side pocket being free to serve as 5 means for communication between the usual side pocket and the secret pocket, a strip sewn between the secret pocket and the usual side pocket, locking means on an edge of the usual side pocket and the strip at the 10 mouth of the secret pocket, said locking means closing communication between the

secret pocket and the usual side pocket, and flexible doubled fingers joined integrally and mounted in the secret pocket between a wall of the secret pocket and the strip, 15 said fingers normally spreading the strip away from the wall of the secret pocket when the locking means on the strip and usual side pocket is disengaged.

In testimony whereof I affix my signature. 20

PAUL SCHERTL.
